BULB OPERATED AQUARIUM CLEANING DEVICE

Allan H. Willinger, New Rochelle, N.Y., assignor to
Aquariums Incorporated, Maywood, N.J., a corporation of Delaware

Filed Aug. 21, 1968, Ser. No. 13,233

Term of patent 14 years

Int. Cl. D30—01

U.S. Cl. D30—12

FIG. 1

FIG. 2

FIG. 3

FIG. 4

FIG. 5

FIGURE 1 is a front elevational view of a bulb operated aquarium cleaning device showing my new design;

FIGURE 2 is a rightside elevational view thereof;

FIGURE 3 is a leftside elevational view thereof;

FIGURE 4 is a top view thereof; and

FIGURE 5 is a bottom view thereof.

The rear of the cleaning device is a mirror image of the front shown in FIG. 1.

The dominant features of the design reside in the portions shown in full lines.

I claim:

The ornamental design for a bulb operated aquarium cleaning device, substantially as shown and described.
